CLAIM

The ornamental design for a voice translator, as shown and described.

DESCRIPTION

FIG. 1 is a perspective view of a voice translator showing my new design, with the lid in a closed position;

FIG. 2 is a top plan view thereof;

FIG. 3 is a front elevational view thereof;

FIG. 4 is a right side elevational view thereof; and

FIG. 5 is a top plan view thereof, with the lid in an open position.

*Fig. 1.**Fig. 2.**Fig. 3.**Fig. 4.**Fig. 5.*
